UNITED STATES PATENT OFFICE

EDWARD H. BAUER, OF WASHINGTON, DISTRICT OF COLUMBIA.

PRIMER FOR GAS-ENGINES.

1,155,871.

Specification of Letters Patent.

Patented Oct. 5, 1915.

Application filed January 14, 1915. Serial No. 2,231.

To all whom it may concern:

Be it known that I, EDWARD H. BAUER, a citizen of the United States, residing at Washington, District of Columbia, have invented certain new and useful Improvements in Primers for Gas-Engines, of which the following is a full, clear, and exact specification.

This invention relates to internal combustion engines and especially to means for priming the cylinders and the saving of gas or fuel and the securing of greater speed with a smaller consumption of fuel.

The principal object of the present invention is to provide a combined primer and gas saver controlled by a single valve operated by the driver or chauffeur.

A further object is to make the primer more effective by taking the gas or fuel directly from the bottom of the carbureter.

Another object is to heat the additional air admitted for the purpose of saving fuel.

Other objects will appear as the description proceeds.

The invention will be first hereinafter described in connection with the accompanying drawings, which constitute a part of this specification and then more specifically defined in the claims at the end of the description.

In the accompanying drawings wherein similar reference characters are used throughout the several views to designate corresponding parts: Figure 1 is a side view of the carbureter, manifold and exhaust pipe of an internal combustion engine, with my combined priming and gas saving device applied thereto. Fig. 2 is a detailed sectional view, on an enlarged scale, of the single valve which controls the primer and gas saver, said valve being shown in the position in which both the primer and gas saver are cut off. Fig. 3 is a similar view of the valve in a position to permit priming. Fig. 4 is a similar view of the valve in the position for admitting an extra supply of air for the purpose of saving gas or fuel, and Fig. 5 is a sectional view through the valve taken at right angles to the sections shown in Figs. 2, 3 and 4, showing the tapered construction of the valve plug and the spring for taking up wear and holding said valve firmly to its seat.

Referring to the drawings, A designates

a carbureter of known construction to which 55 fuel or gas is supplied from a tank (not shown) via pipe a, and from which the mixture of air and gas is delivered to the manifold B by the connection b. A pipe C leads from the bottom of the carbureter A to a 60 three-way valve D from which a pipe E connects to the manifold B, and another pipe F extends close to the exhaust pipe G, being preferably although not necessarily coiled about the same, as shown at f. If desired a 65 T-coupling may be secured at the upper end of the pipe E and said pipe made to communicate with the manifold at a plurality of points instead of at one point as shown in the drawing. The plug d of the valve is 70 tapered, as shown in Fig. 5, and is provided with a spring d' for holding it firmly to its seat and taking up wear. Said valve plug is connected by a universal connection H to a rotatable controlling rod K extending 75 through the dash L of the vehicle or car. Said rod may be fitted with an operating arm or handle M and any suitable indicating means (not shown) may be employed for showing the different positions of the valve. 80 It will be understood, of course, that the operating handle is placed in convenient reach of the chauffeur or driver. The pipe C enters port d² of the valve, while the pipes E and F connect with the ports d³ and d⁴, respectively, of said valve, see Figs. 2, 3 and 4. As illustrated in Fig. 2, the valve plug is turned so as to cut off communication from both of the ports d² and d⁴ with the port d³, that is to say, the pipes C and F are 90 both cut off from the pipe E leading to the manifold. This is the normal position of the valve when the engine is running and there is no occasion for reducing the amount of gas used in the mixture.

When it is desired to prime the engine, the valve plug d is turned to the position illustrated in Fig. 3, establishing communication between the pipes C and E via the ports d² and d³, the port d⁴ and pipe F being cut off. 100 The gas or fuel may then pass from the bottom of the carbureter, where said fuel or gas is richest, directly into the manifold by way of pipe C, valve D and pipe E. The valve being in this position and the engine, 105 of course, hot running, to prime the engine, all that is necessary is to operate the starting crank a sufficient number of times to

cause gasoline to be sucked up into the several cylinders. The valve is then turned to inoperative position, as shown in Fig. 2, and the engine is ready to be cranked and started and it has been demonstrated that by the use of my primer the engine will start after such priming on first turn of the crank.

When it is desired to save gas or fuel, the valve plug d is turned to the position illustrated in Fig. 4, establishing communication between pipes F and E via ports d^4 and d^3 , and cutting off pipe C and port d^2 . In this position of the valve, additional air is admitted to the manifold through pipe F, valve D and pipe E. It will be understood that the outer end of the pipe F is open and that said pipe extends near to the exhaust pipe G of the engine, being preferably coiled about the same, as shown, for the purpose of heating the air before it reaches the manifold, if so desired. Furthermore, the amount of opening for admitting additional air for the purpose of saving gas can very readily be regulated as will be apparent. Likewise in a similar manner the amount of opening of the valve in priming may also be readily regulated or adjusted so as to give a lean or rich mixture, as desired. Furthermore, in the event of the carbureter getting out of order, this device may be so adjusted as to be used temporarily as a carbureter, that is it may be adjusted so as to admit such an amount of gas that will mix with the air coming through the air inlet of the carbureter as to produce the proper mixture to run the motor and enable the operator to reach a point where the carbureter may be repaired. It will be understood, of course, that in so operating the device the manifold becomes in a sense the mixing chamber, the air entering the manifold through the carbureter and the gas entering the manifold through this attachment. It will also be understood that in the use of this device for priming, such act cleans the carbureter taking out any water or sediment that may have collected therein and likewise keeps the carbureter in good condition.

Having thus described my invention what

I claim as new and desire to secure by Letters Patent of the United States is:

1. The combination with the manifold of an internal combustion engine, an exhaust pipe and a carbureter, of a three-way valve, a pipe leading from one port of the valve to the carbureter, another pipe leading from another port of the valve to the manifold, an open air intake pipe extending near to the exhaust pipe and connected to the third port of the valve, and means for operating said valve to selectively establish communication between either the air intake pipe or the pipe leading from the carbureter and the pipe leading to the manifold. 6b

2. The combination with the manifold of an internal combustion engine, an exhaust pipe and a carbureter, of a three-way valve, a pipe leading from one port of the valve to the carbureter, another pipe leading from another port of the valve to the manifold, an open air intake pipe extending near to the exhaust pipe and connected to the third port of the valve, and means for operating said valve to selectively establish communication between either the air intake pipe or the pipe leading from the carbureter and the pipe leading to the manifold, and for closing the three pipes when desired. 75

3. The combination with the manifold of an internal combustion engine, an exhaust pipe and a carbureter, of a three-way valve, a pipe leading from one port of the valve to the carbureter, another pipe leading from another port of the valve to the manifold, an open air intake pipe extending near to the exhaust pipe and connected to the third port of the valve, and means extending within reach from the driver's seat for operating said valve to selectively establish communication between either the air intake pipe or the pipe leading from the carbureter and the pipe leading to the manifold. 85

In testimony whereof I have signed my name to this specification in the presence of two attesting witnesses.

EDWARD H. BAUER.
